(57) CLAIM

The ornamental design for the shaker lid, as shown and described.

DESCRIPTION

FIG. 1 is a top front perspective view of the shaker lid;

FIG. 2 is a side view thereof; and,

FIG. 3 is a top view thereof.

The broken lines in the drawings depict environmental subject matter only and form no part of the claimed design.

1 Claim, 3 Drawing Sheets
